UNITED STATES PATENT OFFICE.

JOHN DANNER, OF CANTON, OHIO.

DESIGN FOR A HAT AND TOWEL RACK.

SPECIFICATION forming part of Design No. 21,407, dated **March 15, 1892.**

Application filed January 29, 1892. Serial No. 419,711. Term of patent 7 years.

To all whom it may concern:

Be it known that I, JOHN DANNER, a citizen of the United States, and a resident of Canton, county of Stark, State of Ohio, have invented a new and useful Design for a Hat and Towel Rack, of which the following is a full, clear, and exact description, reference being had to the accompanying drawings, making part of this specification.

10 My invention relates to a new design for hat and towel racks.

In the drawing the invention is represented in perspective.

The design consists of a frame comprising 15 parallel sides *a*, a curved head *i*, and a straight bar *f*, joining the lower ends of the parallel sides *a*. Secured at different points on the face of the frame are projections *d*, and secured to two of the lower projections 20 is a bar *g*.

H denotes the mirror-frame of rectangular contour and provided with a mirror *k*. This mirror-frame is located between the parallel

sides of the main frame, leaving a space above and below the mirror-frame.

The leading features of the design are the main frame comprising parallel sides *a a*, a straight cross-bar *f*, connecting their lower ends, and a curved bar connecting their upper ends, projections *d*, secured to the face of the frame, and a cross-bar *f*, secured at the lower end of the frame to two of these projections, and a mirror-frame *h*, secured between said parallel sides and leaving a space above and below the mirror-frame, and a mirror 35 placed in said mirror-frame.

I claim—

The design for a hat or towel rack, as herein described and shown.

In testimony whereof I have hereunto set 40 my hand this 6th day of January, A. D. 1892.

JOHN DANNER.
